(57) **CLAIM**

The ornamental design for a trunk for automotive vehicle, as shown and described.

DESCRIPTION

FIG. 1 is a front perspective view of a trunk for automotive vehicle in an environment of use, of the new design; FIG. 2 is a front perspective view thereof;

FIG. 3 is a top plan view thereof;

FIG. 4 is a front elevation view thereof;

FIG. 5 is a side elevation view thereof;

FIG. 6 is a side elevation view thereof, opposite that of FIG. 5;

FIG. 7 is a rear elevation view thereof; and,

FIG. 8 is a bottom plan view thereof.

The broken lines illustrate the environment in which the design is embodied and portions of the trunk for automotive vehicle which form no part of the claimed design.

1 Claim, 8 Drawing Sheets
